(57) **CLAIM**

The ornamental design for an antenna detection probe for a storage tank, as shown and described.

DESCRIPTION

FIG. 1A is an upper perspective view of the antenna detection probe for a storage tank showing my design in a retracted position and a spring mechanism in broken lines.

FIG. 1B is another upper perspective view of the probe in an extended position with a sensor pointed upward and the spring mechanism in broken lines;

FIG. 1C is another upper perspective view of the probe in an extended position with a sensor pointed downward and the spring mechanism in broken lines;

FIG. 2 is a top plan view thereof, with the spring mechanism in broken lines;

FIG. 3 is a bottom plan view thereof, with the spring mechanism in broken lines;

FIG. 4 is a side elevation view thereof, with the spring mechanism in broken lines;

FIG. 5 is an opposite side view thereof, with the spring mechanism in broken lines;

FIG. 6 is a front elevation view thereof,

FIG. 7 is a back elevation view thereof; and,

FIG. 8 is still another front perspective view thereof, showing the spring mechanism and positioning inside a bent pipe within a storage tank in broken lines.

The broken line features are presented for illustrative purposes and form no part of the claimed design.
